UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed May 2, 1925. Serial No. 27,377.

This invention relates to detachable devices for holding small, stiff, work-pieces in vertical typing position against the front of the platen of a typewriting machine, especially for typing along the bottom edges thereof.

To meet the need of an inexpensive card-holder for typewriting machines that may be quickly attached, easily used, and that will gage and hold cards in correct position in the typewriting machine, I provide two simple clips of resilient metal, attachable without the use of tools. These clips are clipped onto the front feed-roll rod of the typewriter by means of transverse spring-loops, lower forked extensions of the clips bearing against the feed-roll-release rod. Each clip has a short lateral tongue bent towards the platen to serve as vertical gages for positioning the bottom edges of the card. The left clip has a short rearwardly-projecting flange on its left edge above the projecting gage-tongues, to serve as a lateral left-hand gage-pin. The forks press against the feed-roll-release rod of the typewriter, and tend to cause the upper portion of the clip to revolve about the front feed-roll rod, and thereby to press against the platen, so as to hold a card securely. Other features and advantages will hereinafter appear.

In the accompanying drawings,

Figure 1 is a sectional view along the lines 2—2 of Figure 2, in the direction indicated by the arrows.

Figure 2 is a partial front elevational view of an Underwood typewriter, showing my invention applied thereto, with a card held in operative position in the clips ready to be typed adjacent its bottom edge.

Figure 3 is a perspective view of the clip arranged for use at the left of the card.

The platen 10 is journaled by means of shaft 11 in frames 12, and is turned by the finger-wheel 13 or a line-spacing mechanism 14. The front and rear feed-rolls 16 and 18 are mounted on shafts 17 and 19. Shaft 17 is journaled in rocking arms 22 rotatable about the rod 20, mounted in side frames 12. The feed-roll-release shaft 21, which is rotatably mounted in the supports 23 mounted on rod 20, is used to release the feed-rolls 16 and 18 by means of a link 24 operating on a crank 25 fastened to the shaft 21.

The clips 31 and 41 are duplicates, except

that the left clip 31 is provided with a small flange-portion 33. The clips are put in position on the typewriting machine by simply snapping the transverse spring loop portions 36 and 46 over the front feed-roll rod with the fingers. The clips each have straight portions or resilient fingers 32 and 42, arranged to stand in upright position in front of said platen 10 tangent to it at the printing line with the upper ends 34 and 44 of said straight portions slightly bent forwardly away from the platen 10 to facilitate the insertion of a card 50 between the platen 10 and the clips 31 and 41. Small, short, integral tongues 35 and 45 are formed out of the straight portions 32 and 42 of the clips toward the platen 10, but may not quite touch it. These tongues serve as vertical gage-pins for the bottom edge of the card 50, and may be so positioned with regard to the printing line (see type 151, Figure 1) of the typewriter that a line of characters 51 can be typed parallel to and as close to the bottom edge of the card 50 as may be desired. The left clip 31 may be provided on its left edge with the short integral inwardly-extending flange 33 positioned below and adjacent said bent upper end 34 to serve as a lateral gage-pin for a card to make easier and more certain the accurate lateral positioning of a card in the clips. To insure that the straight portions 32 and 42 of the clips will be held against the platen with the proper tension to give good typing results on the card 50, fork-like portions 37 and 47 are provided which extend downwardly from the loop-portions 36 and 46 and terminate in two prongs. The fork-like portions 37 and 47 are bent rearwardly enough, so that in operative position on the typewriting machine they bear against the feed-roll-release shaft 21 with enough initial tension to cause the upper straight portions 32 and 42, in effect, to swing around the front feed-roll shaft 17 and bear against the card 50 and the platen 10 back of it, with the proper pressure to hold the card tightly enough against the platen to give good typing results, and yet not too tightly to allow the card 50 to be easily and quickly put in place or removed.

It is expected that the card-holding clips 31 and 41 will be used mostly for typing characters along the bottom edge of the card, as illustrated by the characters 51 on

the card 50 in Figure 2, and in such case the clips will have to be made to order to fit the cards, or vice versa, since the clips are not adjustable. However, sets of clips for several sizes of cards can be easily afforded, since the clips being small and simple in design may be manufactured and sold at a low price.

It can be readily seen that the tongues 35 and 45 can be positioned on the clips, so that they can be used with cards of a certain width, so as to make the characters typed on the card come one or more line-spaces above the bottom edges of the cards.

15 Variations may be resorted to within the scope of the invention, and portions of the improvements may be used without others.

Having thus described my invention, I claim:

20 1. In a typewriting machine including a platen; a set of two clips arranged to be detachably mounted on said machine provided with vertical and lateral gage-pin means, said clips arranged for holding a card vertically in printing position against said platen, said gage-pin means comprising rearwardly-projecting tongues for each of said two clips, and a rearwardly-projecting flange positioned upwardly from said tongue on the 30 left edge of the left one of said two clips.

2. In a typewriting machine provided with a platen; a set of card-holding clips detachably mountable on said machine, said set of clips including resilient fingers pressing a card against the platen and vertical and lateral gages struck from the fingers, for facilitating quick and accurate positioning of the card, in writing position.

3. In a typewriting machine having a platen and a front feed-roll rod; a set of clips arranged for detachable mounting on said rod for holding a card or the like vertically in printing position against said platen, said clips provided with vertical and lateral gage-pin means for positioning the card or the like quickly and accurately in said clips.

4. In a typewriting machine having a platen, a front feed-roll rod, and a feed-roll-release rod; a set of flexible clips arranged for detachable mounting on said front feed-roll rod and arranged for holding a card vertically in printing position against said platen, said clips having lower portions arranged for engagement with said feed-roll-release rod for causing the upper

portions of said clips to be pressed against said platen, said clips provided with vertical and lateral gage-pin means.

5. In a typewriting machine having a 60 platen and a front feed-roll rod; a set of two, flexible, sheet-metal, card-holding clips, each of said clips provided with an integral transverse loop-portion arranged to snap over said front feed-roll rod, and a vertical 65 straight portion above said loop-portion arranged to press tangentially against said platen, said clips provided with vertical and lateral gage-pin means.

6. In a typewriting machine provided 70 with a platen; a set of clips detachably mountable on said machine, said set of clips including resilient fingers pressing a card or the like against said platen, a side-gage 75 associated with said set, and a card-gaging tongue struck from each finger at a selected point along its length, for predetermining the line-space position of the card.

7. In a typewriting machine provided 80 with a platen and a front feed-roll rod; the combination of a set of two clips detachably mounted on said rod, said clips arranged to hold a card or the like vertically in printing position against said platen, each of said 85 clips provided with vertical gage-pin means, and the left one of said clips provided with lateral gage-pin means.

8. In a typewriting machine having a platen, a front feed-roll rod, and a front feed-roll-release rod; a set of two flexible 90 clips arranged with transverse loop-portions for detachable mounting on said front feed-roll rod, straight portions above said loops, and downwardly-extending fork-portions below said loop-portions for engagement 95 with said front feed-roll-release rod, each of said two clips provided with a short, integral rearwardly-extending tongue, the upper ends of said straight portions bent away from said platen, the left one of said 100 two clips provided with an integral rearwardly-extending flange positioned adjacent its bent upper end portion, said clips arranged for holding a card vertically in printing position against said platen.

9. In a typewriting machine having a platen; a set of resilient card-holding fingers pressing a card against the platen, said set carrying gages for vertical and lateral adjustment of the card.
